UNITED STATES PATENT OFFICE

HEINRICH FRÜCHTENICHT, OF BREMEN, GERMANY

SCREEN FOR DUAL-INTENSITY HEADLIGHTS

Application filed July 17, 1931, Serial No. 551,544, and in Germany March 2, 1931.

This invention relates to a dimming device for such head-lights, especially for motor vehicles, which are provided with a dazzling and a non-dazzling source of light.

5 It is known to remove dazzling sources of light from the vision of persons approaching the vehicle by a protecting screen adapted to be actuated from the driver's seat by electromagnetic means. However in the known 10 devices the screen must also be separately operated. This results in that the dazzling source of light could be switched in, without effecting a screening.

15 As compared therewith in the arrangement according to the invention the switching in of the screen is positively connected with the switching in of the large head-light so that therefore in principle the large head-light can be switched in with full intensity of light 20 and nevertheless a dazzling of persons or vehicles coming in the opposite direction cannot occur.

The invention consists in that the electromagnet influencing the protecting screen is 25 switched or series connected in the circuit of the dazzling source of light.

Further features of the invention consist in the peculiar construction of the device.

The invention can be carried out in various 30 manners.

Several embodiments of the invention are illustrated by way of example in the accompanying drawing, in which:—

35 Fig. 1 shows the arrangement in vertical section.

Fig. 2 is a rear elevation of Fig. 1.

Fig. 3 is a diagrammatic view, showing the wiring of the electric magnet.

40 Fig. 4 shows a modified arrangement of the wiring for the electric magnet.

Fig. 5 shows in cross section a form of construction of the arrangement for disengaging and oscillating the screen.

45 According to Figs. 1 and 2 a screen *b* is arranged in front of the head-light lamp *a*, which is provided with a small illuminating element *a'* and a large illuminating element *a''*, the screen *b* being oscillatable around an axle *c*. An extension *b'* of the screen coacts with an electromagnet *d*. Further for block-

ing the screen in inoperative position, that is in swung up position, a locking lever *e* is provided, which is actuated by a second electromagnet *f*. As shown in Figs. 1 and 2, the electromagnet *f* for the locking lever *e* 55 is connected up by means of a wire *h* in the circuit *g* of the large head-light illuminating body *a''*.

If therefore the head-light illuminating body *a''* is switched in by means of a switch *i*, the electromagnet *f* receives current and the locking lever *e* is switched off. The screen *b* can drop into dimming position by means of gravity. The switch *i* serves in known manner also for switching in the small illuminating body *a'*. If the large head-light is switched out, the circuit *l* of the electromagnet *d* can be switched in by actuating a second switch *k* so that by the action of the electromagnet *d* on the extension *b'* 70 of the screen *b* this is returned into inoperative position or swung upwards.

The locking lever *e* is preferably acted upon by a spring *e'* so that, when it is released from the electromagnet *f*, it again fixes 75 the screen in swung up position.

Fig. 2 shows in dot-dash lines that the two switches *i*, *k* can also be positively connected, for example by a rod *m* so that they are simultaneously controlled. 80

As shown in Fig. 3 a single switching lever *i* may be employed for switching in the magnet, which lever leads successively over a plurality of connecting contacts *n*, *n'*, *n''* for the small illuminating body over the magnet *d* and the magnet *f* to the large illuminating body. Consequently first the small illuminating body, then the electromagnet *d* and then the electromagnet *f* for serving the locking lever with the large illuminating body 90 are successively switched in. During the returning of the screen the switch lever is first released and the large head-light illuminating body switched out and then the electromagnet *d* excited for the purpose of swinging up the screen. 95

In the form of construction illustrated in Fig. 4 a separate contact *n*³ is provided for the electromagnet *f*. Thus, when the switch *i* is actuated, the small head-light is switched 100

in by the closing of the contact n , then successively the magnets d and f by closing the contacts n' , n^s and finally the large head-light by closing the contact n^2 . In the arrangement as in Figure 4 the electromagnet f , which in the forms of construction shown in Figs. 1 to 3 is continuously energized so long as the full intensity of the head-light exists, is out of circuit whereby current is economized.

In the construction illustrated in cross section in Fig. 5, a solenoid o serves for actuating the release and oscillation of the screen b , the solenoid first releasing the locking lever e during the excitation, that is, when the large head-light illuminating body is switched in. For this purpose the locking lever e is constructed as an elbow lever. The shiftable solenoid core o' is hingedly connected to the lever e by means of a slot guide p . Further the extended solenoid core o' engages by means of a slot guide q a pin r of the extension b' of the screen b . During the shifting of the solenoid core o' , owing to the excitement of the solenoid o the screen b is first released and then oscillated.

Obviously, for economy in wiring, ground returns may be used in the various circuits, one terminal of each instrumentality being suitably connected to the metal work of the automobile in accordance with the usual construction in such cases.

By means of the invention the advantage is obtained that it is not possible to return the screen into inoperative position, that is to swing same upwards, as long as the large head-light illuminating body burns. Mistakes cannot be made by the operation. Further the switching in of the large head-light illuminating body results in a releasing of the screen so that a reliable dimming of the large head-light light is obtained during its switching in.

I claim:—

1. In a head-light, a reflector, an electric lamp at the focus of the reflector and having a dual intensity filament arrangement, a shade pivoted for vertical swinging movement to the reflector and above the lamp and movable to drop in front of the upper part of the light rays from the lamp, an extension on said shade extending rearwardly of its pivot point and forming a transversely elongated armature, a magnet underneath one end of the armature and positioned to attract the armature and raise the shade upon energization of said magnet, a latch for engaging the remaining end of the armature upon the armature being attracted by the magnet, and electro-magnetic means for releasing said latch.

2. In a head-light, a reflector, an electric lamp at the focus of the reflector and having a dual intensity filament arrangement, a shade pivoted for vertical swinging move-

ment to the reflector and above the lamp and movable to drop in front of the upper part of the light rays from the lamp, an extension on said shade extending rearwardly of its pivot point and forming a transversely elongated armature, a magnet underneath one end of the armature and positioned to attract the armature and raise the shade upon energization of said magnet, a latch for engaging the remaining end of the armature upon the armature being attracted by the magnet, an electromagnet for releasing said latch, circuit connections through said lamp and magnets, and means for closing circuits through the second magnet and the high intensity portion of the filament at one time and for closing circuits through the first magnet and the low intensity portion of the filament arrangement at another time.

3. In a head-light, a reflector, an electric lamp at the focus of the reflector and having a dual intensity filament arrangement, a shade pivoted for vertical swinging movement to the reflector and above the lamp and movable to drop in front of the upper part of the light rays from the lamp, an extension on said shade extending rearwardly of its pivot point and forming a transversely elongated armature, a magnet underneath one end of the armature and positioned to attract the armature and raise the shade upon energization of said magnet, a latch for engaging the remaining end of the armature upon the armature being attracted by the magnet, and electromagnetic means for successively releasing said latch and causing downward movement of the shade.

In testimony whereof I affix my signature.

HEINRICH FRÜCHTENICHT.
